UNITED STATES PATENT OFFICE.

GEORGE F. WOOLSTON, OF NEW YORK, N. Y.

MILLING ATTACHMENT FOR METAL-WORKING MACHINES.

1,294,214.

Specification of Letters Patent. Patented Feb. 11, 1919.

Application filed November 16, 1917. Serial No. 202,308.

To all whom it may concern:

Be it known that I, GEORGE F. WOOLSTON, a citizen of the United States, residing at New York, in the county of New York and 5 State of New York, have invented certain new and useful Improvements in Milling Attachments for Metal-Working Machines, of which the following is a specification.

The present invention has to do with improvements in lathe attachments, this term being employed as a matter of convenience but comprehending the applicability of the device to metal working machines of various types including lathes, milling machines, and similar apparatus.

Attachments for performing the functions of this invention now well known are all limited as to use to such an extent that they are suitable for only certain kinds of work, and in applying them to lathes, for example, especially of small size, so much room is occupied by the mechanism of the attachment that there is little space for handling work. This has led me to devise the 25 present apparatus of such construction as to give it the greatest latitude of adjustment so that it is what may be called a universal construction or one characterized by the absence of the restrictions hitherto observed in apparatus for the same purpose.

To this end the device is intended for attachment to the cross slide of a lathe either directly or indirectly, by a special plate which is furnished, and in combination with 35 the longitudinal movement of the lathe carriage, the transverse movement of its cross slide, and its own adjustment as hereinafter explained, practically all adjustments, horizontal, vertical and angular, may be obtained as desired.

In the accompanying drawings:

Figure 1 is an end elevation of the attachment as applied to a lathe, including the angle plate work table intended for machining sections of rounds, squares, etc., which do not require indexing, said table being tilted at an angle from the horizontal as desired when beveling the end of a section or bar;

Fig. 2 is a vertical sectional view on the plane indicated by the line 2—2 of Fig. 1;

Fig. 3 is a top plan view;

Fig. 4 is a fragmentary view showing the indirect application of the attachment to 55 the lathe as by means of an extension plate;

Fig. 5 is a perspective view of the extension plate alone;

Fig. 6 is a front elevation of a vise attachment for use with this invention;

Fig. 7 is a vertical sectional view on the line 7—7 of Fig. 6;

Fig. 8 is a side elevation of the attachment as applied to a bench miller; and

Fig. 9 is a plan view of the device as shown in Fig. 8.

Referring to the drawings, Figs. 1, 2 and 3 show the construction of the milling attachment as arranged for plain milling, where indexing is not required, the same consisting of the angle frame or standard 1, 70 the vertically adjustable slide 2, and the angle plate work table 3. At one side the standard is provided with a flat base 4 and spaced strengthening ribs 5, while on the other side, its front face, is a guide 6 on 75 which the slide 2 is mounted, said slide being adjustable upwardly and downwardly by means of the handle screw 7. A circular flange 8 projects laterally from the slide and is provided with a circular slot 8' in which 80 are received the T-headed bolts 9, in turn connecting thereto the correspondingly formed flange 10 of the angle plate work table 3 above mentioned.

The flange 10 is formed with a circular tongue 10' fitting in the slot 8' and it will be apparent that this construction permits of completely revolving the work table 3 about a horizontal axis so that work may be held in a horizontal or vertical position, as 90 well as at any angle therefrom. The angle plate work table 3 is slotted as indicated at 11 to receive T-headed bolts 12 holding the clamp 13 for supporting the work on said table. A variety of work can be held 95

on this angle plate work table, as many means are at the disposal of mechanics for clamping various pieces to the table as is now done on milling machines. This table can be inverted and work may be clamped to 100 its under side, which will then be the top, and this will present a larger surface for certain pieces of irregular shape. In such case, if the lathe is large enough so that the table can be lowered sufficiently the work 105 will then come underneath the lathe cutter, but in case of a small lathe where there is not sufficient room underneath the cutter the milling can be done above the cutter just as well.

- The vertical movement controlled by the screw 7 is sufficient to permit of the work being raised any degree required and it can likewise be lowered until the angle plate 5 work table comes in contact with the lathe carriage, thus securing a great adjustment and therefore as much capacity for work as is possible to obtain on any lathe of definite swing.
- 10 The angle plate work table being offset presents one edge to be used when it is advantageous to work the machine close to the cutter and the other edge when it is more advantageous to slide the machine farther 15 away from the cutter. In other words, the particular arrangement above referred to enables the support for the work to be disposed in such relation to the operating tool as to eliminate practically any possibility of shifting of the work from line and the undesirable feature of chattering when pressure is exerted and a considerable cut is being taken. The complete milling attachment is applied to any convenient part of 20 a drill press, lathe or other metal working machine on which it may be used. It is shown in Figs. 1 to 3 fastened by means of a bolt 14 to the cross slide 15 operating on the carriage 16 of a lathe. In Fig. 3 the cross slide 15 is not drawn to its full limit and in this case said slide can be further extended until it comes into contact with the lathe handle 16' and if greater movement is required the rectangular extension 25 plate 17, as illustrated in Figs. 4 and 5, is bolted to the cross slide by means of bolts 18, in which case the lathe attachment is mounted on the plate so that an extension of several inches beyond that secured when 30 directly connected to the slide can be obtained. In other words, the center of the lathe attachment by such arrangement as described will be several inches farther away from the cutter than when the lathe attachment is mounted directly upon the center 35 of the cross slide. This feature is of particular advantage in handling some sections or pieces which can be better manipulated with the machine farther from the cutter.
- 40 In Fig. 4 it is also shown how the machine can be revolved around its supporting bolt 14' in a horizontal circle, thus producing any desired angle in the horizontal. As hereinbefore stated, the plate 17 is bolted 45 to the cross slide by means of the bolts 18 which are made to fit in the circular slot 18' which are usual in cross slides of lathes, and this permits of the compound rest being revolved in a horizontal plane. The bolts 50 are preferably set in countersunk holes so there will be no obstruction preventing the complete revolution of the milling attachment. This extension plate may be drilled to suit conditions as the bolt holes in different lathes vary. Obviously, by means of 55

the rectangular extension plate 17 and the base of the milling attachment bolted thereto, in combination with the slide 2 and the swivel joint provided by the flanges 8 and 10, an exceedingly wide range and variety 70 of adjustment is secured with a correspondingly wide scope of performing milling operations.

As indicating the adaptability of the attachment, I have illustrated in Fig. 8 the 75 application thereof to a bench miller used for plain milling only but which with my attachment allows all of the adjustments necessary for universal milling. The base of this machine is divided into three sections. The bottom section 101 carries a runner 102 which fits into a guide in the slide 103 and by means of the handle screw 104 horizontal 80 adjustment parallel to the screw for producing the same is secured. A handle screw 85 105 is also employed for securing horizontal adjustment at right angles to the adjustment produced by the handle screw 104 just described. The upright 106 is bolted to its base and carries an arm 107 which is bored 90 to receive the spindle 108. Pulleys 109 on said spindle transmit power thereto and on said spindle can be mounted a milling cutter, grinding mill or twist drill, as may be required for whatever work is to be done. 95

The standard 1 of my attachment in this type of machine is applied to the base 110 in whatever position is selected. Likewise the upright 106 may be shifted if required, giving many relative positions of the spindle 100 for driving the cutter and also the spindle of the lathe attachment carrying the work. At 111 is indicated a gear blank which is held under the cutter 112 and in this case the gear blank is mounted directly on 105 the index spindle of the indexing device 113 which will not be specifically described as it forms no part of the present invention, said device being the subject matter of a separate application executed and filed of 110 even date herewith. It is sufficient to say that the device 113 has swivel connection with the standard slide 2 in the manner described with reference to the work table 3 so as to provide for angular adjustment of 115 the work held by this part.

In Figs. 6 and 7 I have illustrated a vise attachment which may furnish a part of the equipment of the lathe attachment hereinbefore set forth. The vise comprises the 120 relatively stationary jaw 114 which is constructed with the flange 115 corresponding in configuration to the flange 10 of the angle plate work table with which this element is interchangeable. A movable jaw 125 116 is vertically adjustable by means of the operating screw 117. Other types of work holding devices may be employed and all of the same will have the proper relative disposition to the main parts of the attachment 130

enabling the scope of adjustment in the different planes which has hereinbefore been referred to and which produces a most practical apparatus for application to the 5 various types of metal working machines that may be required.

Having thus described my invention, what I claim as new is:

1. The combination with a lathe or similar machine and cross slide thereof, and means for producing movement of the slide, of an attachment therefor including a supporting standard, a work holding support mounted on said standard at one 15 side thereof so as to be free to move above and below the plane of the cross slide aforesaid, and a connection directly connecting the said standard to the cross slide and about which said standard is free to completely revolve when above said plane 20 whereby to hold the work at any angle in a horizontal plane.

2. The combination, with a lathe or similar machine having a cross slide, of an attachment therefor including an upright work holding support, the vertical face of which lies in substantially the same plane as the inner edge of the cross slide, said support having an offset base disposed 30 upon the cross slide, and a pivot connection connecting said base to the slide, said support being adjustable about said connection to hold the work at any angle in the horizontal.

3. The combination, with a lathe or similar machine having a horizontally and transversely movable supporting member, of an attachment therefor comprising an upright standard having its base supported 35 on said supporting member, a connecting member connecting said standard to the supporting member and permitting move-

ment of the former completely about the connecting member, a slide mounted on said standard, means for adjusting said slide 45 vertically to points below the plane of the lathe supporting member, and a work holding device having swiveled connection with said slide, whereby to afford longitudinal and transverse adjustments of the work and 50 angular adjustments in both horizontal and vertical planes.

4. The combination, with a lathe or similar machine having a cross slide, of an attachment therefor comprising an upright 55 standard having an angle base offset at one side, a pivot bolt connecting the base of said standard directly to the cross slide, a vertically movable slide mounted on said standard, and means for adjusting said 60 slide, said vertically movable slide having its face provided with an annular flange, and an angle plate work holding device swiveled to the slide and having one edge arranged at a greater distance from its 65 center than the opposite edge, whereby to support the work nearer or farther away from the tool held by the lathe.

5. The combination with a lathe or similar machine having a cross slide, of an attachment therefor comprising a standard 70 formed with a laterally projecting base, work holding means mounted upon said standard, an extension plate secured to the cross slide and adjustable about its connection with the cross slide, and a connection connecting the base of the standard to the extension plate and about which connection said standard is revolvable to adjust 75 the work with respect to the slide and to any angle in the horizontal plane.

In testimony whereof I affix my signature.

GEORGE F. WOOLSTON.
